UNITED STATES PATENT OFFICE.

CHARLES A. GLOEKLER, OF PITTSBURGH, PENNSYLVANIA.

COUNTER-GUARD.

1,008,813.

Specification of Letters Patent. Patented Nov. 14, 1911.

Application filed April 3, 1911. Serial No. 618,690.

To all whom it may concern:

Be it known that I, CHARLES A. GLOEKLER, a citizen of the United States, residing at Pittsburgh, in the county of Allegheny and State of Pennsylvania, have invented new and useful Improvements in Counter-Guards, of which the following is a specification.

My present invention pertains to counter-attachments; and it consists in the peculiar and advantageous counter guard hereinafter described and particularly set forth in my claims appended.

In the accompanying drawings which are hereby made a part hereof: Figure 1 is a perspective showing my novel guard embodying bars of plate glass and as properly applied to a counter. Fig. 2 is an enlarged detail view, partly in section and partly in elevation, showing one of the brackets or shelf-supports of the guard and also showing the arm on the upright member of the shelf-support as turned outward so as to make the shelf extend a maximum distance outward or forward with respect to the counter. Fig. 3 is an enlarged detail section taken at a right angle to Fig. 2 and illustrating the manner in which the plate-glass bars are attached to the upright member of the intermediate bracket or shelf support, and also showing the apertures in the upright member for the reception of metallic bars when such bars are used in lieu of the plate-glass bars, as is shown in Fig. 4. Fig. 4 is a perspective view of a modified construction in which longitudinal metallic bars are employed; said construction being shown as properly applied to a counter. Fig. 5 is a horizontal section taken through the said modified construction in a plane below the arms on the upright members of the brackets. Fig. 6 is an enlarged detail vertical section taken in a plane at one side of the vertical member of one bracket. Fig. 7 is a detail perspective of one of the arms on which the shelf of the guard is disposed.

Referring by letter to the said drawings: A is a counter which may be of the ordinary construction or any other construction consonant with the purpose of my invention.

B is the shelf of my novel counter-guard which is preferably of marble, though I would have it understood that it may be made of wood, glass, metal, or any other suitable material without affecting my in-

vention or involving departure from the scope thereof as claimed.

C are the end brackets or shelf supports of the guard, and D is the intermediate bracket or shelf support comprised in the guard. Each of the said brackets or shelf supports comprises a fixture a fixedly connected to the face of the counter at a slight distance below the top thereof and having a vertical bore b, an upright member, preferably tubular as shown, extending through the said bore b of the fixture a, and having by preference an ornamental lower end appurtenance c and also having diametrically opposite depressions d in its upper portion, a set screw e bearing in the fixture a and extending through the wall of the bore b and designed to be fixed against the upright member to adjustably fix the same in the fixture and at the height desired, and an arm f mounted on the upper end of the upright member and designed to be fixed thereto in an adjustable manner by a set screw g, and having at its ends upstanding projections h, designed to rest in recesses i in the underside of the shelf B, Fig. 6, with a view to preventing casual horizontal slipping or displacement of the said shelf. The upright member of each of the end brackets C is lettered j, and the upright member of the intermediate bracket D is lettered j². Each of the upright members j is provided in its inner side—i. e., its side adjacent the intermediate bracket, with three (more or less) apertures k, Figs. 1 and 2, and as shown in said figures, a channeled support E, preferably formed of sheet-metal and closed at its bottom l, is detachably connected to the said inner side by screws m. The upright member j² of the intermediate bracket D is provided in its opposite sides with apertures k²; the said apertures being arranged in three (more or less) pairs and the apertures comprised in each pair being alined as shown. It will also be noted by reference to Fig. 3 that the upright member j² of the intermediate bracket D is provided with two supports E similar to the one hereinbefore referred to, the said supports E being connected to the member j² by suitable screws m.

In addition to the elements thus far specifically described, the embodiment of my invention shown in Figs. 1 to 3 comprises two bars F of plate-glass or other glass suitable to the purpose. Each of the said

plate-glass bars is arranged at its outer end in the support E of one end bracket C, and at its inner end in one of the supports E of the intermediate bracket D, and hence it 5 will be manifest that there is no liability of the said bar being accidentally displaced while the counter-guard is in use.

By reason of the construction shown in Figs. 1 to 3, it will be manifest that an efficient counter-guard is provided and one 10 that is calculated to enhance rather than detract from the finished appearance of a counter while effectually performing the functions ordinarily possessed by counter-guards. It will also be understood that because of the adjustable fixing of the upright members of the brackets in the fixtures *a* thereof, and through the medium of the set screws *e*, the arms *f* and the shelf B thereon 15 may be adjustably fixed at various heights above the top of the counter to suit different conditions. In Fig. 1, the major portion of the shelf B is made to overhang the counter, this because of the major portions of the 20 arms *f* being extended inward or rearward from the upright members of the brackets and so as to overhang the top of the counter. It will be noticed, however, by reference to Fig. 2, that the arms *f* may be reversed and 25 may be adjustably fixed in reversed position on the upright members and so as to cause the major or longer portions of the said arms to extend outward or forward from the upright members, and in that way bring 30 about the support of the major portion of the shelf B in a position in front of the vertical plane of the counter. The upright members of the brackets are preferably of circular form in cross-section to permit of 35 the arms *f* being swung horizontally on the upright members from one position to the other after the set screws *g* are loosened. The said formation of the upper ends of the 40 upright members is not, however, essential, inasmuch as the end stated may be attained by removing the arms from the upright members and replacing the arms in reversed 45 position on the upright members.

When it is desired to employ longitudinal 50 metallic bars *F*³, Figs. 4 and 5, in lieu of the glass bars F shown in Figs. 1 and 3, the said glass bars F and the supports E therefor are removed from the upright members of the brackets, and the metal rods *F*³ or rods 55 of any other suitable material are placed in the apertures in the upright members of the end brackets and intermediate bracket, in the manner shown in Figs. 4 and 5—that is to say, the end portions of the said bars are 60 arranged in the upright members of the end brackets, while the intermediate portions of the bars are made to extend through and are supported by the upright member of the intermediate bracket.

65 It will be gathered from the foregoing

that the general construction of my counter-guard is such that either glass bars F may be employed, or bars such as *F*³, and that when the guard is equipped with glass guards F, it may be readily changed so as 70 to comprise in lieu of the bars F, bars such as *F*³, and vice versa; it being simply necessary when the guard embodies the construction shown in Figs. 4 and 5, and it is desired to change to the construction shown in 75 Figs. 1 to 3, to remove the bars *F*³, and apply the supports E and the glass bars F to the upright members of the brackets. It will also be gathered that the general construction of the counter guard contributes to 80 cheapness in production, inasmuch as when the upright members of the brackets are provided with the apertures *h* and *h*³ and with apertures to receive the screws *m*, the counter-guard may be equipped with the glass bars F and the supports or holders therefor, or may be simply equipped with the bars *F*³, according to the election of a customer; the 85 construction shown in Figs. 4 and 5 being less expensive than that shown in Figs. 90 1 to 3.

While I have shown and described certain forms of my invention, it is to be understood that I am not limited to the details or the form or relative arrangement 95 of parts disclosed, but that modifications may be made therein within the scope of my invention as defined by my claims appended. For instance in lieu of arranging the shelf as shown, said shelf, especially 100 when made of thick marble, may be seated on the arms *f* entirely between the projections *h* and so as to extend above said projections.

Having described my invention, what I 105 claim and desire to secure by Letters-Patent, is:

1. In a counter guard, the combination with brackets comprising horizontal fixtures adapted to be attached at their rear ends to the face of a counter and having vertical bores in their forward portions and also having set screws bearing in and extending through the walls of the said bores, and vertical members extending through the bores 115 of the fixtures and adjustably fixed to the fixtures by the set screws thereof; of bars carried by the vertical members of the brackets and extending between the vertical members and adjustable vertically together with 120 said members in a plane in front of the counter to which the horizontal fixtures are attached.

2. In a counter-guard, the combination of spaced brackets comprising upright portions 125 and upright holders on the sides of said upright portions; the said holders being of U-shape in horizontal section and closed at their lower ends and open at their upper ends, and a glass bar extending between two 130

of the holders and having its ends arranged in the holders and supported on the closed lower ends thereof.

3. In a counter guard the combination 5 with brackets adapted to be attached to a counter and having upright members and also having reversible arms detachably fixed on the upper ends of the upright members, each of said arms having a long portion at 10 one side of the upright member and a short portion at the opposite side of said member; of bars carried by and extending between the upright members of the brackets, and a shelf supported on the arms of said brackets.
- 15 4. In a counter-guard, the combination with brackets comprising fixtures adapted to be attached to a counter, upright members adjustably fixed to the fixtures and adjustable vertically with respect to the same, and 20 reversible arms detachably fixed on the upper ends of the upright members, each of said arms having a long portion at one side of the upright member and a short portion at the opposite side of said member; of bars

carried by and extending between the upright members of the brackets, and a shelf supported on the arms of said brackets. 25

5. In a counter-guard, the combination with brackets adapted to be attached to a counter and having upright members and 30 depressions in opposite sides of the upper portions thereof, and also having reversible arms mounted on said upright members and provided with set screws to seat in the depressions thereof, each of said arms having 35 a long portion at one side of the upright member and a short portion at the opposite side of said member; of bars carried by and extending between the upright members of the brackets, and a shelf supported on the 40 arms of said brackets.

In testimony whereof I have hereunto set my hand in presence of two subscribing witnesses.

CHARLES A. GLOEKLER.
